UNITED STATES PATENT OFFICE.

JOHN F. BEHLMER, OF NEW YORK, N. Y.

CARBONIC-ACID-GAS GENERATOR.

SPECIFICATION forming part of Letters Patent No. 357,696, dated February 15, 1887.

Application filed May 8, 1886. Serial No. 201,624. (No model.)

To all whom it may concern:

Be it known that I, JOHN F. BEHLMER, of the city and county of New York, in the State of New York, have invented a new and useful Improvement in Carbonic-Acid-Gas Generators, of which the following is a specification.

My invention is applicable to generators wherein marble dust or other substance is subjected to the action of acid in order to generate carbonic-acid gas; and the invention relates to that class of generators which comprise an acid-receptacle mounted upon trunnions or journals, so that it is capable of turning in order to pour from it the required quantity of acid into the generator.

The invention will hereinafter be particularly described; and it consists in novel combinations of parts, which are pointed out in the claims.

In the accompanying drawings, Figure 1 represents an elevation of a portion of a generator-vessel and a longitudinal section of an acid attachment surmounting the same and embodying my invention. Fig. 2 is an end view of the generator-vessel and a transverse section of the acid attachment upon the plane of the dotted line $x-x$, Fig. 1; and Fig. 3 is an end view looking from the left hand of Fig. 1, a handle which is upon the journal of the acid-receptacle being removed.

Similar letters of reference designate corresponding parts in the several figures.

A designates a generator-vessel, which is of the ordinary or any suitable character, and to which, considered alone, my invention does not relate.

Surmounting the generator-vessel A is a casing, B, which may be made of metal and which, as here shown, is of barrel-like or drum-like form and closed at the ends by heads B'. This upper casing, B, communicates with the generator-vessel A by a throat or passage, C, and it has at the top opposite the throat or passage C a corresponding opening, b, which is closed by a cap or cover, b'. Within the casing B is the acid-receptacle D, which is, as here shown, of barrel-like form, and which has at the top an inlet-opening, d. It is my intention to make the acid-receptacle D of glass, and it has at opposite ends studs or projec-

tions d', to which may be applied, by screw-threads or otherwise, the journals d², on which the vessel D is pivoted. These journals d² may be fitted, one of them to a closed bearing, d³, at one end of the casing B, and the other of them to a stuffing-box, d⁴, at the opposite end of the casing B, and through which that journal is prolonged, so as to receive a handle or hand-wheel, d⁵, for turning it.

From this description it will be seen that the acid-receptacle D is journaled at opposite ends, so that it may turn readily in a plane transverse to the length of the casing B. When the acid-receptacle is turned to the position shown, its opening d is immediately below the opening b in the top of the casing B, and by removing the cap b' acid in suitable quantity may be introduced into the receptacle D. The receptacle D may at the proper time be turned upon its axis more or less, in order to pour through the opening d a desired quantity of acid, and the quantity so discharged may be gaged or regulated by means of a notched wheel, e, upon one of the journals d², with which engages a pawl or detent, e', as best shown in Fig. 3. This locking and regulating device not only serves to prevent the accidental turning of the acid-receptacle D, but by it also the extent of turning the receptacle, and consequently the amount of acid poured therefrom through the opening d, may be gaged or regulated.

In order to properly control the acid which is poured out of the receptacle D into the throat C and to prevent it from coming in contact with the metal casing, I employ a shield or guard, E, which I also intend to make of glass, and which rests upon the bottom of the interior of the casing B and has a funnel-like mouth or neck, e², projecting downward into the throat or passage C. This shield or guard E is prolonged upward at the ends near to the journals e² of the acid-receptacle D, and is carried upward at the sides of the receptacle D, as shown in Fig. 2, so as to shield or guard the opening d. The acid-receptacle D is intended to be turned in the direction indicated by the arrow in Fig. 2, and on the side toward which the opening d is carried in turning the receptacle the shield E is prolonged upward nearly to the top of the recep-

tacle D, as shown in Fig. 2, and also by the dotted and full lines in Fig. 1. Consequently any acid which may tend to slop over or pour out of the receptacle when it is nearly full is prevented by this upward extension of the shield or guard E from slopping against the interior of the metal casing B, and by the construction of this shield or guard the acid is all directed to the central outlet-neck or funnel-mouth e^2 .

In order to afford a free space around the shield or guard E and between it and the interior of the casing B, so that all parts of the interior of the casing shall receive the same pressure that is within the generator, I have represented the casing B as provided with projections b^2 from its interior surface at the lower portion thereof. These projections may be made in the form of semicircular ribs or 20 flanges, and on them the shield or guard E rests and is supported.

This apparatus is very desirable, because the parts with which the acid comes in contact may be made of glass, and because there are 25 no valves which may get out of order and leak.

What I claim as my invention, and desire to secure by Letters Patent, is—

1. The combination, with a generator-vessel and an upper casing communicating therewith by a throat, of an acid-receptacle having an opening in its top and journaled in the casing, and a shield or guard within the casing partly surrounding the acid-receptacle, and having a funnel outlet or neck extending downward 35 into the throat between the upper casing and the generator-vessel, substantially as herein described.

2. The combination, with the generator-vessel and the upper casing, B, communicating therewith by a throat, C, and having projections on the lower portion of its interior, of the shield or guard E, resting on the bottom of the casing and provided with the outlet funnel or neck e^2 , and the acid-receptacle 45 journaled in the casing and turning within the shield or guard, substantially as herein described.

JOHN F. BEHLMER.
